UNITED STATES PATENT OFFICE.

AMY A. SHERMAN, OF ITHACA, NEW YORK.

DESIGN FOR A CURTAIN.

SPECIFICATION forming part of Design No. 27,634, dated September 7, 1897.

Application filed May 20, 1897. Serial No. 637,454. Term of patent 3½ years.

To all whom it may concern:

Be it known that I, AMY A. SHERMAN, a citizen of the United States, residing at Ithaca, in the county of Tompkins and State of New York, have invented and produced a new and original Design for Curtains, of which the following is a specification.

The drawing is an elevation of a curtain, showing the new design.

10 The design is applied to curtains and draperies, as A.

One leading feature of my design consists in the representation of a plural number of growing plants or vines, the pattern of each 15 being distinct or unrepeated in the others. The several stalks or main stems of the plant are seen at the base, and each vine is shown distinct and of different pattern from the others.

20 Another feature consists of the design of

a plural number of plants, as already described, on a curtain, commencing at the bottom or lower horizontal edge, as C, and adjoining or nearer to one vertical edge, as D, than the other, leaving on the curtain adjacent said other vertical edge a space of some width between the plants and edge. 25

It is obvious the design may be printed or woven in the curtain fabric and that the curtain may be used singly or in pairs. 30

I claim and desire to secure by Letters Patent—

The design for curtains and draperies as herein shown and described.

In testimony whereof I affix my signature 35 in the presence of two witnesses.

AMY A. SHERMAN.
